CLAIM

The ornamental design for a combination arm rest and storage container, as shown and described.

DESCRIPTION

FIG. 1 is a perspective view of a combination arm rest and storage container, showing my new design;

FIG. 2 is a rear elevational view thereof in the closed position;

FIG. 3 is a cross-sectional view taken along lines 3—3 of FIG. 2;

FIG. 4 is a front elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a top plan view in the open position.

FIG. 4.

FIG. 5.

FIG. 6.

FIG. 7.

FIG. 8.

FIG. 9.
